Primary Examiner — Karen E Eldridge Powers

(57) CLAIM

The ornamental design for glove ornamented with a map of the state of Alaska, as shown and described.

DESCRIPTION

FIG. 1 is a top view of the right hand glove with all fingers extended; and,

FIG. 2 is a top view of the right hand glove with the three outermost fingers folded in.

The broken lines in the drawings illustrate the wearer's wrist and form no part of the claimed design.
